UNITED STATES PATENT OFFICE.

JAMES D. RIVES, OF ATLANTA, GEORGIA, ASSIGNOR OF ONE-FOURTH TO J. W. BLOSSER,
OF ATLANTA, GEORGIA.

BUILDING CONSTRUCTION.

1,037,321.

Specification of Letters Patent. Patented Sept. 3, 1912.

Application filed February 16, 1912. Serial No. 678,099.

To all whom it may concern:

Be it known that I, JAMES D. RIVES, a citizen of the United States, residing at Atlanta, in the county of Fulton and State 5 of Georgia, have invented certain new and useful Improvements in Building Construction, of which the following is a specification.

The present invention relates to building 10 constructions and particularly to an improved frame building provided with an exterior coating or veneer of concrete or other plastic material.

An important object of my invention is to 15 provide a structure of the above mentioned character, which will be to a high degree proof against weather conditions, largely fire resistant, and which can be cheaply constructed.

20 In accordance with my invention I provide a hollow wall including an inner open frame-work. Upon the inner face of this frame-work are placed furring strips, to which are secured laths. These laths are 25 covered with a coating of plastering. Upon the outer face of the frame-work are secured boards forming a sheathing, which is preferably provided upon its exterior face with a section of water-proof paper or like mate- 30 rial. Secured in spaced relation to the outer face of the sheathing or boards is a net-work of reinforcing wires. I provide anchor-wires, preferably disposed in the mesh openings of the wire netting. These anchor 35 wires are secured to the boards by staples or the like, which also serve to hold the water-proof paper in place upon the sheathing or boards.

In practice I have found it advantageous 40 to extend the end portions of the anchor-wires through the mesh-openings of the reinforcing net-work, which prevents the displacement of these anchor-wires when the soft concrete is poured about them. The anchor-wires are of desired lengths and are 45 bent in serpentine form so that they will not be exposed by extending beyond the outer face of the coating or veneer of concrete. A mold is placed at a suitable spaced 50 distance from the sheet 9, depending upon the desired thickness of the coating or veneer of concrete to be formed, and the concrete is

55 poured into the space formed by the mold and the sheathing. The concrete is allowed to harden and the mold is subsequently removed. By my construction a hollow wall is provided, comprising an open interior frame-work supporting relatively thin spaced outer walls of plastic or cementitious material. Air is permitted to circulate or 60 is circulated through the opening in the hollow wall, such air keeping the various portions of the wall dry.

65 In the accompanying drawings forming a part of this specification and in which like numerals are employed to designate like parts throughout the same, Figure 1 is a perspective view of a portion of my improved building construction or wall, with parts progressively broken away to more 70 clearly show details of construction, Fig. 2 is a transverse vertical sectional view through the completed wall, Fig. 3 is a horizontal cross-sectional view through the completed wall taken at one corner thereof, and, 75 Fig. 4 is a perspective view of one of the anchor-wires.

80 In the drawings wherein for the purposes of illustration, I have shown a preferred embodiment of my invention, the numeral 1 designates a sill of an upstanding open intermediate frame-work. At each end of this sill is a post 2, connected at its upper end with a horizontal plate 3. A securing strip 8^a is attached to the post 2 and 85 connected midway its ends with a purlin 4. Upon the inner face of the open frame-work are secured upstanding furring strips 5, connected at the ends thereof with the sill 1 and the plate 3, as shown. Upon these furring strips are secured laths 6, preferably horizontally arranged. These laths serve to support and hold an inner coating of plastering 7. Upon the outer face of the open frame-work is disposed a sheathing, formed of 90 boards 8, preferably vertically disposed and secured to the sill 1, the purlin 4, and plate 3 by nails or other means. Disposed upon the outer face of this sheathing is a sheet of 95 water-proof material 9, preferably water-proof paper commonly termed "tarred felt". Secured upon the boards 8 are horizontal and vertical spacing strips 10 and 11. The horizontal spacing strips 10 extend the en- 100

tire length of the wall and are placed adjacent the upper and lower ends thereof. The vertical spacing strips 11 are always placed at the corners of the wall and about openings for doors and windows (not shown).

5 The numerals 12 and 13 designate vertical and horizontal reinforcing wires of an open fabric or net-work. The vertical wires 12 are attached at their ends to the boards 8 and extending over or about the horizontal strips 10 are held in spaced relation from the sheet 9. The horizontal reinforcing wires 13 are attached at their ends with the boards 8 and extending about the vertical strips 11 are held in spaced relation to the sheet 9. It is thus seen that this open fabric or net-work formed of the reinforcing wires is securely attached to the boards 8 and retained spaced therefrom. Preferably disposed within the mesh openings of the wire net-work are anchor-wires 14, which are attached to the boards 8 by staples 15 or other means. These staples in addition to connecting the anchor-wires with the boards 8 also serve to connect the sheet 9 with such boards. The anchor-wires 14 are bent into vermiciform or serpentine shape, as shown, and they may be thus bent prior to being secured in place or secured in place while straight and subsequently bent to a desired curvature. Care is taken that the turns, twists or kinks produced should extend laterally in waves between the sheet 9 and the outer surface of a coating or veneer 16. It is desirable that the anchor-wires 14 should extend diagonally toward and from the boards 8, thus also forming waving reinforcing lines longitudinally and perpendicularly and in as many diverse directions as may be convenient. These anchor-wires reinforce laterally, the outer coating or veneer of concrete 16, and also serve to anchor or attach such coating to the boards 8. The anchor-wires 14 are interwoven more or less with the reinforcing wires 12 and 13 and project through the mesh openings so as to engage with the wires 12 and 13, in order that their free ends may not be displaced by the descending stream of concrete, which is employed to form the coating 16. The vertical and horizontal wires 12 and 13 extend through and are embedded in the longitudinal central axis of the concrete coating 16 and serve to reinforce the same vertically and longitudinally. In addition to the above named function of the anchor-wires 14, they coöperate with the wires 12 and 13 and aid them in reinforcing the concrete coating 16. This joint action of the reinforcing wires 12 and 13 and the anchor-wires 14 is a very important feature of the invention, as jointly they produce results that could not be had by the employment of either set alone. The anchor-wires 14 reinforce the coating 16 horizontally and per-

pendicularly, anchor or bind it to the sheathing of boards 8, and being deflected outwardly from their points of attachment on the sheathing and again inwardly toward the sheathing, they bind the inner and outer longitudinal halves of the coating 16, so as to prevent any cleavage of the same along the medial line, wherein are disposed the reinforcing wires 12 and 13. This concrete coating or veneer is formed by placing a face mold 18 forwardly of and suitably spaced from the sheet 9, depending upon the desired thickness of the coating 16 to be obtained.

The concrete is of a proper consistency so that it may be freely poured between the mold 18 and the sheet 9. It is thus seen that the reinforcing wires 12 and 13 and the anchor-wires 14 will all become securely embedded in the material of the coating or veneer 16. The wires 12, 13 and 14 being spaced as shown, form an open structure, which allows of the free feeding of the soft concrete into place, such concrete entirely surrounding the wires, forming no pockets and completely excluding the air. It is thus seen that by the practice of my invention the concrete surrounds and embeds the wires at every point, effectually excluding the air and preventing corrosion which is so detrimental to many metal reinforced concrete walls. As soon as the veneer or coating of concrete 16 has sufficiently hardened, the face mold 18 is raised an appropriate distance and more cement poured in and allowed to set and harden. This process is continued until the wall or the structure is completed.

It is well known that concrete or cement structures are more or less pervious to water. This is the case with a solid wall formed of concrete or the like and even with a hollow wall of such material, having a dead air space. It is thus seen that moisture would pass through the concrete coating 16 and ultimately come in contact with or effect the sheathing formed of the boards 8. These boards would thus expand or contract with the change in the weather conditions. The distortion of the boards 8 by the expansion or contraction thereof will exert great force upon the coating 16 through the anchor wires 14 and other elements. Even if the reinforcing means of this coating should hold, it is obvious that the coating as a whole would work loose from the boards, and hence become liable to be cracked or otherwise damaged. In a hollow wall with a dead air space, air in such space collects and holds the moisture which damages the structure, besides making the building cold and damp. I overcome these disadvantages by providing means to cause a circulation of air in the opening of the hollow wall, whereby the various parts of the wall are kept dry.

To accomplish this the sill 1 is provided upon its outer face with a lower inlet air opening 1* having communication with the atmosphere exteriorly of the building. The 5 circulating or drying air entering through the opening 1* passes upwardly through the hollow wall and discharges through an outlet opening 20 formed upon the plate 3. It is thus seen that the heat from the interior 10 of the building or room of which this wall forms a part, will heat the air within the opening of the hollow wall and cause the continuous circulation of the air through such hollow wall, the air entering through 15 the opening 1* and discharging through the opening 20, as above stated. This circulation of the air is free and in all directions, both vertical and horizontal. In this connection particular attention is called to the 20 arrangement of the purlin 4 and strip 5, as shown. The purlin 4 is spaced from the plastering 7, which allows of the free passage of the circulating air therebetween in a vertical direction. The strip 5 is spaced 25 from the boards 8, and allows of the free horizontal circulation of the air therebetween. I have found that this means of circulating air through the hollow wall operates satisfactorily to keep the different parts 30 of the wall dry. I have found it advantageous under certain conditions to feed heated air into the opening 1*, from a hot air furnace (not shown). It is obvious that such heated air will circulate through the 35 hollow wall and be discharged through the opening 20. If desired, suitable openings (not shown) may be made through the plastering 7, whereby some of the heated air circulating in the hollow wall may pass into 40 the room to warm the same. It is thus seen that I provide a wall simulating a solid stone or concrete wall, but being free from any of their disadvantages, and possessing superior qualities. My wall may be made 45 for a fraction of the cost, is moisture-proof to a high degree, almost as durable, quicker to erect, and is strong and neat in appearance.

It is to be understood that the form of my 50 invention herewith shown and described is to be taken as a preferred example of the same and that numerous changes in the arrangement of parts may be resorted to with-

out departing from the spirit of the invention or the scope of the subjoined claims. 55

Having thus described my invention, I claim:—

1. In a building construction, a hollow wall comprising an upstanding wooden main frame, sheathing boards secured upon the outer face of the main frame in close relation to each other, an open wire fabric having its edges securely attached to the sheathing boards, a plastic wall engaging the outer surface of the sheathing boards and having the open wire fabric embedded therein, anchor-wires bent in serpentine form and corresponding approximately in number to the mesh openings of the wire fabric, the free end portions of the anchor-wires being embedded transversely in the plastic wall, and elements attaching the anchor-wires between their ends with the sheathing boards, whereby the plastic wall is connected with the sheathing boards uniformly throughout its entire area. 75

2. The combination with a supporting structure, of a plastic wall, a reinforcing open metal fabric embedded axially in the plastic wall and attached to the supporting structure, and anchor-wires attached between their ends to the supporting structure and having their end portions bent in serpentine forms to extend in divers directions in the plastic wall, the anchor-wires co-acting 80 with the open metal fabric to reinforce the plastic wall in all directions. 85

3. The combination with an upstanding supporting structure, of a plastic wall disposed adjacent one side thereof, a reinforcing open metal fabric embedded in the plastic wall to extend longitudinally thereof, and anchor-wires securely attached to the supporting structure and having their free end portions bent in serpentine form to extend 90 in divers transverse directions in the wall, to co-operate with the open metal fabric for reinforcing the plastic wall in all directions. 95

In testimony whereof I affix my signature 100 in presence of two witnesses.
